UNITED STATES PATENT OFFICE

OSCAR C. BICKEL, OF JAMAICA, NEW YORK, ASSIGNOR TO FOREMOST FABRICS CORPORATION, OF NEW YORK, N. Y., A CORPORATION OF DELAWARE

DESIGN FOR A TEXTILE FABRIC

Application filed November 11, 1930. Serial No. 37,626. Term of patent 3½ years.

To all whom it may concern:

Be it known that I, OSCAR C. BICKEL, a citizen of the United States, and a resident of Jamaica, county of Queens, State of New York, whose post-office address is 392 Fifth Avenue, city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design.

A repeat unit of the design is illustrated on the drawing in full lines enclosed by dot and dash lines, while the extension of such unit is indicated in dotted lines showing the relation of the design unit to the preceding and succeeding ones.

I claim:

The ornamental design for a textile fabric substantially as shown and described.

OSCAR C. BICKEL.
